Primary Examiner — Kevin K Rudzinski*Assistant Examiner* — Amber J Rabie(74) *Attorney, Agent, or Firm* — Joseph F. Murphy; Potomac Law Group, PLLC(57) **CLAIM**

The ornamental design for an apron, as shown and described.

DESCRIPTION

FIG. 1 is a front plan view of the apron in accordance with my new design, with the straps of the apron being shown in an exemplary folded orientation, it being understood that each of the straps is linear when extended and laid flat; and, FIG. 2 is a front view of the apron shown in FIG. 1 but in the state where it is shown worn on a mannequin.

The stippled stitching pattern along the periphery of the apron form part of the design. The remaining broken dashed lines in the various figures are directed to unclaimed portions of the apron and form no part of the claimed design. The broken dotted lines in the various figures are directed to a mannequin on which the apron is shown in a state like that when worn by a person. The mannequin does not form any part of the claimed design. The apron is shown with a symbolic break in length. The appearance of any portion of the article between the break lines forms no part of the claimed design.
